UNITED STATES PATENT OFFICE

94,168

DESIGN FOR A BRIDGE FOR EYEGLASSES

Fred H. Soden, Rochester, N. Y., assignor to Continental Optical Company, Inc., Rochester, N. Y., a corporation of Indiana

Application October 10, 1934, Serial No. 53,541

Term of patent 3½ years

To all whom it may concern:

Be it known that I, Fred H. Soden, a citizen of the United States of America, residing at Rochester, in the county of Monroe and State of New York, have invented a new, original, and ornamental Design for a Bridge for Eyeglasses, of which the following is a specification, reference being had to the accompanying drawing forming a part thereof.

In the drawing:

Fig. 1 is a view in front elevation, and
Fig. 2 is a plan view.

I claim:

The ornamental design for a bridge for eyeglasses, as shown.

FRED H. SODEN.
